UNITED STATES PATENT OFFICE.

JAMES W. FARRELL, OF NORWOOD, OHIO.

DESIGN FOR A BACK FOR TOILET MIRRORS, BRUSHES, OR SIMILAR ARTICLES.

43,139.

Specification for Design.

Patented Oct. 15, 1912.

Application filed August 2, 1912. Serial No. 713,012. Term of patent 3½ years.

To all whom it may concern:

Be it known that I, JAMES W. FARRELL, a citizen of the United States, residing in Norwood, in the county of Hamilton and State of Ohio, have invented a new, original, and ornamental Design for Backs for Toilet Mirrors, Brushes, or Similar Articles, of which the following is a specification, reference being had to the accompanying drawing, forming part thereof.

The figure is a plan view of a toilet mirror, showing my new design.

I claim:

The ornamental design for a back for toilet mirrors, brushes, or similar articles, as shown.

JAMES W. FARRELL.

Witnesses:

CHARLES M. BODMER,
THOMAS A. MACKLIN.
